CONTINUOUS CASTING MACHINE

Joseph L. Hunter, Riverside, Calif., assignor to
 Hunter Douglas Corporation, Riverside, Calif.,
 a corporation of Delaware

Application May 17, 1950, Serial No. 162,510

9 Claims. (Cl. 22—57.4)

1

This invention relates to continuous casting machines, and has for its principal object the provision of an improved horizontally arranged machine for the continuous casting of one or more metal bars which may be cut to any desired length. The casting machine of the invention has proved itself capable of producing continuous lengths of cast metal bars that are remarkably free of shrinkage cavities and porosity, and which may be rolled readily to thin gauge strip of high quality. For example, the machine has been used with outstanding success in the continuous casting of aluminum bars approximately one inch thick which have been subsequently reduced by rolling to gauges of 0.010 inch and less for use as Venetian blind strip stock without cracking or the development of surface defects of any substantial character.

In the new casting machine, the mold cavity is defined by a cooperating pair of endless chains of articulated mold blocks, and means are provided for revolving each of said chains about its own center. The chains are mounted so that over a portion of their length they are in engagement one with the other and define between them a mold cavity having walls which move continuously as the respective chains are revolved together at the same linear speed. Coolant passageways are formed in each of the mold blocks, and coolant is supplied thereto and withdrawn therefrom through rotatable coolant distributors connected to the coolant passageways by lengths of flexible hose or other flexible couplings. Provision is made for rotating each coolant distributor in synchronism with the endless chain of mold blocks to which it is connected by the flexible couplings, whereby a continual stream of coolant may be passed through each mold block at all times during revolution of the endless mold block chains.

The coolant passageways of each alternate mold block on each chain are advantageously connected to the coolant passageways of one of the adjacent intervening blocks, and the rotatable coolant distributor is formed with separate coolant inlet and outlet chambers. Flexible couplings connect the distributor inlet chamber to the coolant passageways of said alternate blocks, and separate flexible couplings connect the distributor outlet chamber to the coolant passageways of the intervening blocks. Thereby coolant flows from the distributor inlet chamber through the coolant passageways of the alternate blocks, then back to the distributor outlet chamber through the coolant passageways of the intervening blocks.

2

In each pair of mold blocks whose coolant passageways are interconnected, the alternate block (which receives fresh coolant from the distributor inlet chamber) is advantageously the block that is the last to come in contact with molten metal during each revolution of the chain, and the intervening block (from which coolant is returned to the distributor outlet chamber) is the block which first comes in contact with molten metal during each revolution of the chain. Thereby each block, as it comes in contact with the molten metal, is at substantially a constant temperature determined by the temperature of the coolant.

Molten metal is delivered to the interior of the traveling mold through a spout of such cross-sectional size and shape as to fit closely within the mold cavity. The spout thus forms a plug at one end of the horizontal mold cavity which prevents molten metal from flowing out that end before it has solidified. The spout is advantageously formed at the end projecting into the mold cavity with a central face perpendicular to the axis of the mold cavity and with side faces swept back therefrom at a substantial angle. Passages for conveying molten metal to the mold open to the mold cavity at each of said faces. Thereby molten metal is delivered into contact with the traveling side walls of the mold shortly in advance of the delivery of metal to the center of the mold cavity. In this manner solidification of the molten metal at the sides of the cast bar is caused to occur sufficiently in advance of solidification of metal at the center of the bar so that any shrinkage pipe tending to form at the bar center is kept filled with molten metal delivered through the passage terminating at the central face of the spout.

The solid cast bar of metal emerging from the traveling mold is engaged by a pair of pinch rolls driven (advantageously through an interconnection with the drive for the mold block chains) at a speed just about equal to the linear speed of travel of the mold blocks less the linear rate of thermal contraction of the cast bar between the point of solidification thereof and the point of engagement by the pinch rolls. In this manner the cast bar is relieved of longitudinal stresses which might otherwise cause it to crack or break in the region where its temperature is so close to its melting point as to make it mechanically weak.

The foregoing and other features of the new casting machine are described below in greater detail with further reference to the accompanying drawings, wherein:

55 Figure 1 is a side elevational view of the entire

apparatus for carrying out the casting operation, showing the melting furnace, casting machine, cut-off shears, and the entrance end of a holding oven;

Figure 2 is an enlarged perspective view of the casting machine, as seen from the end into which the molten metal is introduced;

Figure 3 is another perspective view of the casting machine, as seen from the end at which the bar leaves the machine;

Figure 4 is a top plan view of the machine;

Figure 5 is an enlarged sectional view of the same, taken along the line 5—5 in Figure 4;

Figure 6 is an enlarged transverse sectional view through the driving end of the upper chain of mold blocks, taken along the line 6—6 in Figure 5;

Figure 7 is a sectional view through one of the mold blocks, taken at 7—7 in Figure 6;

Figure 8 is an enlarged, fragmentary sectional view taken at line 8—8 in Figure 5;

Figure 9 is a perspective view of the feed spout through which the molten metal is introduced into the mold cavity;

Figure 10 is a transverse sectional view through the spout, taken at 10—10 in Figure 9;

Figure 11 is a longitudinal horizontal section through the spout, taken at 11—11 in Figure 9;

Figure 12 is a horizontal section through two adjacent mold blocks, as seen at 12—12 in Figure 6;

Figure 13 is an elevational view of the driving mechanism at the rear of the machine;

Figure 14 is an elevational view of the mechanism for driving the coolant distributor heads, as seen at 14—14 in Figure 4;

Figure 15 is an enlarged sectional view through one of the distributor heads, taken along the line 15—15 in Figure 4; and

Figure 16 is an enlarged longitudinal vertical section through the flying shear mechanism which cuts the bars off at predetermined lengths, so that the bars can be stored in the holding oven, taken at 16—16 in Figure 4.

Referring first to Figures 1 to 4, the reference numeral 20 designates a melting furnace of the open hearth reverberatory type, which supplies molten metal to a continuous casting machine 22. The casting machine comprises an endless chain of mold blocks which, in the apparatus shown in the drawings, form two traveling mold cavities for the purpose of casting two bars simultaneously. The mold blocks of the machine are cooled by fluid coolant circulated from and back to a coolant distributor 24. Beyond the casting machine 22 are pinch rolls 26 which engage and drive the bars of metal cast by the machine, and beyond the pinch rolls is a flying shear cut-off 28 that cuts the bars off to a predetermined length so that they can be stored in a holding oven 30, or otherwise handled.

The furnace 20 comprises a main housing 31 enclosing the melting hearth, and an external holding well 32 connected therewith, from which the molten metal is drawn through a tap hole, indicated at 33, during operation of the casting machine. The molten metal discharged through the tap hole 33 runs down a channel-shaped launder 34 to a box 35 at the entrance end of the casting machine 22, and thence through two spouts 36 into the two mold cavities of the machine. Both the launder 34 and box 35 are made of a suitable refractory material to withstand the high temperature of the molten metal. The box 35 is supported on a horizontal shelf 40 which is formed integrally with the supporting struc-

ture of the machine, and the launder 34 is secured to the wall or other structure of the furnace well 32 adjacent to the tap hole 33. The box 35 is divided by a partition 41 into two chambers 42 and 43 which feed the two spouts 36 (Figure 4), and these chambers are connected by openings 44 with the channel of the launder 34 near the bottom thereof, so that the metal flowing down the launder is admitted to the chambers.

The box 35 rests on a plate 45 which is secured to the top of shelf 40, and is clamped tightly against the rear end of the spouts 36 by means of a screw 46 (Figure 2) which is threaded through a tapped hole in an upstanding flange 50 of an angle bracket 51, the horizontal flange of which is welded or otherwise secured to the plate 45. The end of screw 46 bears against a protective metal plate 52 on the side of launder 34, clamping the latter tightly against the box 35, and holding the box against the ends of the spouts 36. The spouts 36 are themselves connected to a transversely extending, horizontal angle iron 53 (Figure 5) in a manner to be described in more detail hereinafter; the said angle iron 53 being welded or otherwise fixedly attached to the shelf 40.

Referring now to Figures 5 to 8, the casting machine 22 is seen to comprise a pair of endless chains of articulated mold blocks 60, each of 30 said chains being trained around horizontally spaced pairs of drive sprockets 61 and driven sprockets 62, and one of said chains being disposed directly above the other and parallel thereto. The top chain of blocks is designated generally by the reference numeral 63, and the bottom chain by the numeral 64. The two chains are driven in opposite directions by their respective drive sprockets 61, so that the bottom course of the top chain 63 and the top course of the bottom chain 64 travel together from left to right, as seen in Figure 5, and at the same rate of speed.

Each of the mold blocks 60 is a massive block of hard, dense cast iron or steel, ground on all sides and in the machine as shown, having two shallow channels 65 and 65' (see Figures 2, 3 and 6) formed in the outer face thereof. Each of the channels 65, 65' constitutes one half of the mold cavity for one of the bars of metal cast by the machine, and when the mating blocks of the adjacent courses of the top and bottom chains are brought together in proper registration with one another, they form a pair of laterally spaced, open end mold cavities of uniform cross section that extend longitudinally through the center 55 of the machine. Transverse alignment of the mating mold blocks within extremely close tolerances is obtained by means of small rectangular end plates 67 which are secured by screws to opposite ends of each block in the top chain 63 and project outwardly for a short distance beyond the outer face of the block to form flanges that fit snugly down over the ends of the companionate block in the bottom chain 64. The bottom block is thus confined between the end plates 67, and is prevented thereby from shifting transversely with respect to the top block; hence the two blocks are always maintained in accurate transverse alignment with one another during the period of their conjunction.

As best shown in Figures 6 and 7, each of the mold blocks 60 is provided with a plurality of closely spaced transverse cylindrical bores 66 of small diameter, the said bores lying in a horizontal plane just below the bottom surfaces of the channel 65, 65'. These bores 66 are passages

which carry the water or other fluid coolant that removes the heat of the molten metal from the blocks 60, and their connections with the coolant circulating system will be described in detail presently. The passages 66 may conveniently be formed by drilling holes into the block from one end thereof, stopping just short of the far end, and then driving tapered plugs 68 into the open ends of the holes, as shown in Figures 6 and 12.

One thing that should be noted at this point is the close proximity of the fluid passages 66 to the bottom of the mold cavities 65, 65', as this is an extremely important factor in eliminating any tendency of the block 60 to bow upwardly as a result of unequal expansion between the top and bottom sides of the block. The magnitude of the distortion problem becomes immediately evident when it is realized that during operation of the machine, the channels 65, 65' are filled with molten metal (e. g. molten aluminum at 1250° F. to 1400° F.), whereas the opposite side of the block may be at only 70° to 80° F. By placing the coolant passages 66 as close as possible to the bottom of the channels 65, 65', the mass of metal heated by the molten metal is reduced to the minimum, and the rate of heat transfer to the coolant is accelerated due to reduction of metal thickness through which the heat must travel. In order to counteract the expansive force of even the small mass of metal lying above the passages 66, it is desirable to provide a large mass of metal on the opposite side of the passages, which remains cool, and therefore is relatively unaffected by the heat of the aluminum, and to this end the underside of the block 60 is provided with an integral massive transverse rib or buttress 70 of solid metal which reinforces and stiffens the block against bending forces.

The ends of the rib 70 are cut back from the ends of the block 60, as shown in Figure 6, to provide space for chain (or hinge) links 71 which connect the blocks together to form the endless chains 63 and 64. The links 71 are secured by bolts 72 to the underside of the blocks 60, and are staggered on alternate blocks so that the projecting ends of adjacent links interengage by overlapping. These overlapped ends of the links are drilled through to receive pin bolts 73, and the latter extend all the way through from one side of the block 60 to the other, thereby providing a hinge pin connection for the links at both sides of the block. The pins 73 are located with their centers in the planes of the vertical contact surfaces of the blocks 60 at the front and back sides thereof; thus, when the blocks are traveling in a straight line, adjacent faces of each pair of interconnected blocks are laid flat against one another, forming an unbroken surface from one end of the straight section of chain to the other.

The ends of the pins 73 project beyond the outer links on both sides, and mounted thereon are ball-bearing rollers 74 which run on the peripheral edges of rigidly supported side plates 75. Each of the side plates 75 is elongated horizontally, with straight top and bottom edges and semicircular ends having their centers of curvature at the axes of the sprockets 61 and 62. The side plates 75 of each chain 63, 64 are mounted on a supporting structure 80 located at one side of the chain mold assembly, and are attached thereto by a pair of laterally spaced, thick-walled steel pipes 76 of large diameter which project horizontally outward from a side wall plate 79 of the supporting structure 80 between the sprockets 61 and 62.

The structure 80 is made up of heavy steel plates welded together at their edges to form a closed, box-like member of great strength and rigidity, and is advantageously provided with a base plate 89' that is bolted down to the floor. The pipes 76 are closed at their outer ends, and are secured by bolts 81 to the supporting structure 80, the said bolts passing all the way through the supporting structure as shown in Figure 4.

10 The driving sprockets 61 are welded or otherwise suitably fixed to drive shafts 85 between and immediately adjacent plates 75, the said shafts extending through circular openings in the plates. The outer end of the shaft 85 terminates in a threaded stud on which a nut 78 is screwed, and the latter is drawn up tight against a collar 77 that bears against the outside of the outer sprocket 61. Each of the driving sprockets 61 is rotatably supported by a double row ball bearing 86 and a single row ball bearing 87 mounted respectively at the opposite ends of an eccentric bore within a sleeve 88. The sleeve 88 extends through and is rotatable within aligned circular openings 89 and 90 in the front and back wall 79 and 81, respectively, of the supporting structure 80. Sleeve 88 is held against axial and rotational movement with respect to the housing 80 by means of bolts 92 which pass through arcuate slots 93 (see Figure 3) in a radial flange 94 at the end of the sleeve 88 projecting from the side wall plate 79. The slots 93 are concentric with the axis of the sleeve 88, and thus permit a limited amount of rotation of the sleeve, whereby the tension in the chains 63, 64, can be adjusted by virtue of the eccentricity of the shaft 85 relative to the outer surface of the sleeve.

40 The driven sprockets 62 are likewise fixed to shafts 85' corresponding to shaft 85, and the same are rotatably supported by antifriction bearings mounted within a flanged sleeve 88', one end of which appears in Figure 2. The principal difference between the supports for shafts 85 and 85' is that the latter are fixed in position, and are not provided with the eccentric chain tension adjustment of the former.

45 A spur gear 95 is mounted on the end of the upper shaft 85 where it projects from the back of the supporting structure 80, and is secured against rotation relative thereto by means of a key or the like. A corresponding spur gear 95' is secured to the lower sprocket drive shaft, as shown in Figure 13, which is an elevational view of the drive mechanism for the casting machine. The top gear 95 is meshed with an idler gear 96, which is meshed, in turn, with another idler gear 97 that is also meshed with the bottom spur gear 95'. The idler 97 meshes with a pinion 98 mounted on a shaft 99, and the latter is driven by a sprocket 100 through a friction clutch 101, which is adapted to slip when overloaded, and thus protects the mold chains and driving mechanism from damage in the event that something becomes jammed.

60 Idler gear 96 is mounted on a shaft 102, which is journaled in one end of an arm 103. The other end of the arm 103 is swingably adjustable about a journal portion 104 provided on a cap 105 that is bolted to the outer end of the sleeve 88, as shown in Figure 6. The journal portion 104 is concentric with the axis of the top sprocket drive shaft 85, and the arm 103 thus maintains a constant center-to-center distance between gears 95 and 96, even though the shaft 85 may be swung through an arc during adjustment of the tension of the top chain 63.

Gear 95, is, of course, carried with shaft 85 during any such adjustment of the latter, and arm 103 causes gear 96 to be shifted with gear 95. Once the proper adjustment of shaft 85 has been obtained, arm 103 is rigidly secured to the supporting structure 80 by a screw 106 which passes through a slotted hole in the arm and fits loosely therein.

The other idler gear 97 is mounted on a short stub shaft 107, which is likewise maintained at a constant center-to-center distance with respect to gear 95'. In this instance, shaft 107 is journaled in an arm 108 intermediate the ends thereof. The right-hand end (Fig. 13) of arm 108 is supported for swinging movement about the axis of the bottom sprocket drive shaft 85, and shaft 99 is journaled in the left-hand end of the arm. Arm 108 maintains a constant center-to-center distance between shafts 85, 107, and 99, and also permits the bottom shaft 85 to move through an arcuate path during adjustment of the tension of the bottom chain 64. Here again, when proper adjustment of shaft 85 has been obtained, arm 108 is rigidly secured to the housing 80 by a screw 109 which passes through a slotted hole in the arm and fits loosely therein.

Trained around the sprocket 100 is a roller chain 110 which extends downwardly to and is trained around a sprocket 111 mounted on the drive shaft of an electric motor 112. A second sprocket 116 (Figure 4) on the motor shaft drives another chain 113 which is trained around a large sprocket 114 on shaft 115, to drive the pinch rolls 26. The electric motor 112 also drives the rotatable heads of the coolant distributor 24, and to this end, a sprocket 120 is mounted on the bottom drive shaft 85, which drives a chain 121 that is trained around another sprocket 122 on a shaft 123.

Shaft 123 extends forwardly through the supporting structure 80 (as shown in Figure 3) and is journaled at the other end in a pillow block 124 (Figure 14) mounted on one vertical edge of a housing 125 that supports the coolant distributor mechanism 24. As shown in Figure 14, a sprocket 126 on shaft 123 drives a chain 130 which is trained around sprockets 131 and 132, and also around an idler sprocket 133. The purpose of the idler sprocket 133, is to enable the chain 130 to be carried around one side of sprocket 132 and around the opposite side of sprocket 131, so that the two sprockets are driven in opposite directions. Sprocket 131 drives the upper distributor head 134 of the unit 24, while sprocket 132 drives the lower distributor head 135 thereof.

The housing 125 is preferably constructed of steel plates welded together to form a box-like structure having a base plate 140 that is bolted to the floor. The housing 125 is also connected to the supporting structure 80 of the casting machine by two heavy steel bars 141 and 142 (Figure 3) which locate the distributor heads 134 and 135 centrally between the ends of the upper and lower chains 63 and 64.

Fixedly mounted in opposite side walls of the housing 125 are sleeve bushings, such as that shown at 143 in Figure 15, and journaled for rotation in these bushings are pipes 144 and 145 (shown in cross section in Figure 14). Pipe 145 and its associated distributor head 135 are similar in construction to pipe 144 and its distributor head 134, and therefore only the latter assembly will be described in specific detail with reference

to Figure 15, although it will be understood that the description applies also to the lower unit. Sprocket 131 is secured to pipe 144 near one end thereof, and welded to the other end on the opposite side of the housing 125 is a closed, cylindrical drum 150 (see particularly Figure 15), which is divided by a partition 151 into two chambers 152 and 153. Extending through the center of pipe 144 is a smaller pipe 154 one end of which passes through an opening 155 in partition 151 and thus communicates with chamber 153. Leakage through the clearance between pipe 154 and opening 155 is prevented by two O-ring seals 156.

Mounted on the other end of the pipe 144 beyond the sprocket 131, as best shown in Figures 1 and 4, is a swivelled fluid coupling 160 which connects a water supply pipe 161 to the inner pipe 154, and a fluid discharge pipe 162 to the annular space between pipe 154 and the walls of pipe 144. The fluid supply pipe 161 is connected to a pipe 163 which is connected, in turn, to the output side of a water pump 164 driven by a motor 165. The intake side of the pump 164 is connected by a pipe 166 to a tank 170 near the bottom end thereof. The discharge pipes 162 are also connected into the tank 170, and thus there is a certain amount of recirculation of the water in the tank, for reasons which will presently be explained.

Cold water from any suitable source, such as a well or the city mains, is discharged into the tank 170 through a pipe 171, the end of which extends down to the bottom of tank 170, so that cold water is discharged close to the suction end of pipe 166, whereby a certain portion of the cold water is taken directly into the pump 164, while the balance is mixed with the warm water discharged by pipes 162. An overflow pipe 172 emptying into a drain (not shown) is connected into the tank 170 near the upper end thereof, and warm water is thus allowed to escape at the same rate that cold water is added. A valve 173 in line 171 permits adjustment of the rate of flow of cold water into the tank 170, so that the proportion of newly added cold water to the total volume of water being circulated through the mold blocks can be regulated over a wide range to give any desired water temperature.

The water delivered by pump 164 is discharged into the inner pipe 154, and (see Figure 15) empties into chamber 153 of the distributor drum 150. A plurality of equidistant, angularly spaced elbow fittings 174 corresponding in number to one-half of the number of mold blocks 60 of the upper or lower chain blocks, as the case may be, are screwed into the drum 150 so that they communicate with chamber 153. The elbow fittings 174 are connected by lengths of flexible hose 175 (Figures 2 to 4) to nipples 176 (Figure 6) projecting laterally from the adjacent ends of alternate blocks 60. As best shown in Figures 6, 7 and 12, each nipple 176 is screwed into a tapped hole 68, which intersects another hole 181 at right angles thereto and at a slightly higher level. Hole 181, in turn, intersects the bores 66 extending transversely across the mold block, and thus serves as a manifold to distribute the water or other fluid coolant uniformly to all the coolant bores 66 therein.

At the opposite end of each block, the bores 66 are again intersected by a cross hole 182 which is intersected, in turn, by a tapped hole 183 extending into the block from the end thereof. Both of the holes 181 and 182 are conveniently

formed by drilling holes into the block 60 from the leading or trailing edge thereof; the said holes being stopped just short of the distant edge, and being tapped at their open ends to receive a tapered pipe thread plug 179, as shown in Figure 7. A threaded elbow nipple 184 is screwed into the tapped hole 183, and clamped to the nipple is a short, U-shaped flexible hose 185, which extends inwardly toward the center about which each endless chain revolves in its travel along the periphery of the plate 75, the other end of said hose being connected to another elbow nipple 186 in the next adjoining block 60 as shown in Figure 12. The construction of all of the blocks is identical, and water passed through one block, say the right-hand block in Figure 12, and discharged through nipple 184 and hose 185 is therefore returned through the adjoining block (i. e. the left hand block as seen in Figure 12) to another nipple 190, which is connected by a return length of flexible hose 191 to one of a second set of elbow fittings 192 (Figure 15) on the distributor head. The elbow fittings 192 are screwed into the drum 150 on the left-hand side of partition 151, and therefore are connected into chamber 152. In this way, fluid returning from the mold blocks is sent back through the space between pipe 154 and pipe 144 to the swivel joint 160, where it is emptied into tank 170 through line 162.

The cooperative operation of the chains of mold blocks and the distributors described above is as follows: When the motor 112 (Figure 13) is energized, the mold block drive gears 95 and 95' are rotated in opposite directions, thus turning the upper and lower sprockets 61 (Figure 5) in opposite directions so that the upper and lower mold block chains 63 and 64 revolve in opposite directions about the geometric centers of their respective supporting side plates 75. The upper chain of mold block 63 revolves in a counterclockwise direction, as viewed in Figure 5, and the lower chain of mold block 64 revolves at the same speed in a clockwise direction. Thus a moving mold traveling at a constant speed (to the right as viewed in Figure 5) is defined between the engaging mold blocks on the lower course of the upper chain 63 and on the upper course of the lower chain 64.

As the endless chains of mold blocks are revolved, the distributor heads 134 and 135 (Figure 3) are driven in synchronism therewith by the shaft 123, which is operatively connected to the driving mechanism of the mold block chains. As described above, the sprocket 131 (Figure 14) through which the upper distributor is rotated turns in the opposite direction to the sprocket 134 through which the lower distributor 135 is rotated. The size of these sprockets (and of the other sprockets in the distributor drive) are so chosen that the distributors each make just one complete revolution for each complete revolution of the chains of mold blocks about their respective geometric centers. Thus the upper distributor 134 (Figures 2 and 3), which is connected by one set of hoses 175 and 191 to the upper mold block chain 63, rotates in the same direction as and substantially in synchronism with that chain, and the lower distributor 135 rotates in the same direction as and substantially in synchronism with the lower block chain 64 to which it is connected by the lower set of hoses 175 and 191. The distributors are positioned so that their axes of rotation lie respectively on projections of the axes of revolution of the mold block chains 63 and 64.

As the chains of mold blocks revolve, the coolant distributors rotate with them, permitting the flexible coolant hoses 175 and 191 to be carried continuously around and around with the mold blocks to which they are connected. In this manner a continual stream of coolant is enabled to flow from the distributors 134 and 135 through the mold blocks of the respective chains 63 and 64 and back again to the respective distributors, without the hoses either becoming entangled with one another or interfering in any way with revolution of the mold block chains.

One important factor that should be brought out at this point is that each pair of mold blocks connected together by the U-shaped hose section 185 is connected to its associated distributor head 134 or 135 so that the water is circulated first through the trailing block of the pair, and then is returned to the distributor head through the leading block of the pair. The advantage of this arrangement is that a high degree of uniformity of temperature is obtained at the mold block encountered by the molten metal issuing from the feed spout, regardless of whether it is the leading or trailing block of an interconnected pair. This is due to the fact that at the instant the leading block moves into position to receive the molten metal from the feed spout, the water circulating through the passages 66 is at the same temperature as the water entering the trailing block, since the latter will not yet have been heated up by the hot metal. Thus, if the temperature of the water entering the trailing block is 60° F., it will still be at 60° F. when it enters the leading block (the cavities of which are now filled with molten metal) on its return trip to the distributor. As the trailing block of the pair moves into position to receive the molten metal, it will of course still be at 60° F., and from this it will be evident that the walls of the mold cavity will always be at a relatively uniform temperature at the instant of contact by the molten metal. The maintenance of uniform mold block temperatures is important, because the grain structure and other physical characteristics of the metal are greatly influenced by the rate at which the metal is chilled. Thus, a temperature difference between adjoining blocks would result in objectionable variations in grain size and structure along the length of the bar. The importance of maintaining an absolutely uniform mold block temperature diminishes after the metal has been initially chilled, and any slight temperature differential between the trailing and leading blocks as the mold blocks continue their travel through the machine has no apparent ill effect on the bar cast by the machine.

The feed spouts 36 by which molten metal is fed into the traveling mold assembly are shown in detail in Figures 9, 10, and 11, and each is seen to comprise a centrally bored, two-piece body 195 of insulating refractory material enclosed within a rectangular, box-like steel case 196. Projecting from one end of the case is a tip 197 of insulating refractory material, which is shaped to conform closely to the cross sectional contour of the mold cavity, but is provided with clearance on all sides to permit free movement of the mold blocks past the same. The length of the feed spout is governed by the position of the terminal end of the tip 197 within the mold cavity. In order to prevent molten metal from escaping through the crack between adjacent blocks as the latter come together after passing around the sprockets 62, it is necessary that the tip 197 project into the

mold cavity to a point not less than 1 block width beyond the centerline of the sprockets 62.

The case 196 comprises side plates 198 to which top and bottom plates 199 and 200 are secured by countersunk screws 201. The top plate 199 is somewhat shorter than the bottom plate 200, and formed in the inner faces of the exposed end portions of the side plates 198 are vertically extending notches 202 which receive tongues 203 projecting laterally from opposite sides of the tip 197 at the base end thereof. The tip 197 is thus keyed to the side plates of the case by a tongue and groove connection, and is conveniently inserted into the case or removed therefrom by merely slipping the back end of the tip down into the open notches 202. Metal cheeks or lands 204 are secured by screws to the outsides of the side plates 198 at the extreme ends thereof, and these are contoured to fit the sides of the mold cavity. The cheeks 204 provide solid backing for the extreme outer edges of the tip 197, and protect the latter against breakage or excessive abrasion in the event that the spout becomes slightly misaligned within the mold cavity.

At the rear end of the case 196, the top, bottom, and side plates have vertical notches 205 formed therein to receive keys 206 that fit into notches in the inside faces of two laterally spaced blocks 210. The blocks 210 are welded or otherwise fixed to the top of angle iron 53, and are spaced apart just far enough to receive the rear end of the case between them. With the case thus keyed to the blocks 210, the spout is solidly held in place, and the box 35 can be clamped tightly against the rear ends of the two spouts, as described earlier.

The refractory body 195 of the feed spout is preferably made of two pieces for convenience in removing the solid plug of metal that freezes in the passages 211 each time that the machine is shut down. The passages 211 extend longitudinally through the body 195 from one end to the other, and may be drilled out, as shown in Figure 10, or formed in any other suitable manner. The rear end of the body 195 projects slightly beyond the end of the metal case 196, and terminates in a perfectly square, flat face 212 which abuts against the outside of the box 35, with the passages 211 registered with openings 213 (Figure 5) in the box, through which the molten metal flows from the box into the spout.

The extreme outer end of the tip 197 is preferably formed as shown in Figure 11, with a center face 214 perpendicular to the axis of the spout, and two outwardly facing, slightly concave faces 215 that are swept back at an angle of about 35° to the face 214. Three outwardly diverging passages 216 are formed in the tip; one going to each of the three angularly related faces. The purpose of this tip configuration is to promote freezing of the metal at the sides of the mold first, so that the shrinkage cavity that tends to form in the cast bar as the metal solidifies and cools can be fed and filled by molten metal issuing from the center passage 216. The water-cooled mold blocks chill the metal so suddenly that freezing of the molten metal occurs almost instantaneously, and the bars are probably solid all the way through, although somewhat mushy in character, within a very short distance from the tip. The progressive freezing of the bars from the sides in toward the center that is obtained with the tip just described, enables the fluid metal discharged from the middle passage to keep full the shrinkage cavity that

would otherwise be likely to form, until the center of the bar finally solidifies, and as a result the bars produced by the machine are sound and entirely free of shrinkage pipes and porosity.

One highly important feature of the invention has to do with the manner whereby the tip 197 acts to seal the back end of the mold cavity against leakage of molten metal. As mentioned earlier, the tip 197 is shaped to conform closely to the cross sectional contour of the mold cavity, and is provided with clearance on all sides to permit free movement of the mold blocks past the tip. This clearance may range from a few thousandths of an inch up to $\frac{1}{64}$ or more, and the highly fluid, molten metal under a head of several inches in the box 35, has a tendency to flow into the same. However, the cold mold blocks extract heat so rapidly from the molten metal in the corner at the junction of the tip face with the block, that the metal is chilled locally and becomes viscous or slushy, with a thin skin formed on its surface which prevents penetration of the metal into the crevice between the tip 197 and the mold blocks.

As the mold blocks move away from the tip, the skin is ruptured, and fluid metal flows back into the corner, where it is again chilled and another skin formed on the surface. This process is repeated with great rapidity all of the time that the machine is in operation, producing a faintly rippled surface on the bars; each ripple being from $\frac{1}{64}$ to $\frac{1}{32}$ inch in width. Thus, the combination of cold mold blocks and a feed spout tip that conforms closely on all sides to the cross sectional contour of the mold cavity, yet without being in actual contact therewith, provides an arrangement wherein ample clearances are provided between relatively moving parts, so that excessive wear of the tip and abrasion of the mold blocks is prevented, and at the same time, a sealing action is obtained that prevents the molten metal from flowing into the clearances.

On leaving the machine at the exit end thereof, the bars of metal are guided laterally into the pinch rolls 26 between outer rollers 220 and tandem inner rollers 221 (Figure 4) which are rotatably supported on a horizontal shelf 222 projecting laterally from the supporting structure 80. The pinch rolls 26 comprise an upper roll 223 and a lower roll 224 which extend transverse to the direction of travel of the cast bars, and which are rotatably supported at their ends in bearing blocks 225. The bearing blocks 225 are slidable vertically between laterally spaced pairs of guide posts 226, which are mounted on a horizontal shelf plate 230 projecting laterally from the side of the supporting structure 80, the top ends of each pair of posts being connected together by a bridge member 231. Long bolts 232 extend upwardly through the shelf 230, guide posts 226, and bridge member 231 to secure the side frames into a solid structure. An adjusting screw 233 is threaded downwardly through the bridge member 231 and engages the top bearing block 225 to adjust the spacing between the rolls 223, 224.

The bottom roll 224 is connected at its back end to the sprocket shaft 115 (Figure 13) and is driven thereby in the clockwise direction, as viewed in Figure 5; the top roll 223 being driven by the bottom roll in the opposite direction and at the same rate of speed through a pair of intermeshed gears (not shown) which are enclosed within a housing 234 (Figures 3 and 4).

As best shown in Figures 3 and 5, the two

rolls 223, 224 are water cooled, and to this end are provided with cylindrical bores 235 (Figure 5), through which a pipe 236 of somewhat smaller outside diameter is passed. Fitted on extensions of the roll necks and pipes 236 beyond the gear housing 234 are swivel couplings 240 which deliver water to the inner pipe 236 and exhaust the water from the space between the pipe and the walls of the bore 235. The inlet sides of the couplings 240 are connected to pipes 241 which are joined together and connected to the main water pipe 171; while the outlet side of the couplings is connected to a pipe 242 (Figures 1 and 3) that returns the used water to the tank 170.

The rolls 223 and 224 have two important functions: First, they are driven at a speed carefully computed to regulate the speed of the bars to the linear speed of the chains 63, 64, less the linear rate of thermal contraction of the cast bars that has taken place between the point in the machine where the metal becomes solid and the point of contact of the rolls 223, 224; and second, they perform the work of pushing the bars into the holding oven 30, thereby relieving the chains 63, 64, of this relatively heavy load. The first-named function is important because of the low tensile strength of most metals at temperatures near the melting point. Aluminum, for example, is characteristically hot short at temperatures just below its melting point, and in the hot-short temperature range the tensile strength of the metal is substantially zero. The rapid cooling of the metal in the casting machine causes a very considerable amount of shrinkage in the bar, and if the bar is allowed to leave the mold blocks at the same speed as the linear travel of the chains 63, 64, the lengthwise shrinkage of the bar within the mold cavities of the machine will cause the bar to pull apart or at least crack, in its weak, hot-short zone. The pinch rolls 223, 224 hold back on the bar so that the amount of shrinkage is taken up, and the exit speed of the bar from the machine is somewhat less than the linear speed of the chains 63, 64. The proper peripheral speed of the pinch rolls is obtained by proportioning the sprockets 114 and 116 so that a rotational speed is obtained which is correct for the diameters of the rolls 223 and 224.

The second-named function is important where long lengths of bar have to be pushed into the oven. In such instances, the work required to overcome friction of the bar sliding over its supports within the oven may exceed the pushing capacity of the casting machine, since the machine has only the friction of the mold blocks on the bars to drive the latter, and in that case the mold blocks would merely skid along the bars. The pinch rolls 223, 224 may be tightened down onto the bars by the adjusting screw 233 to secure a powerful frictional grip thereon.

As the bars leave the pinch rolls, they are engaged on their outer edges by two guide rolls 250 (Figures 3 and 4) which are supported on a narrow shelf 251 projecting laterally outward from the supporting structure 80 at the extreme end thereof.

Beyond the guide rolls 250, the bars pass through the flying shear cut-off 28, where they are automatically cut to predetermined lengths while continuing in motion. The flying shear cut-off (best shown in Figures 3 and 16) is essentially a hydraulically operated shear mounted on a freely movable carriage that is adapted to

travel with the bars while the latter are engaged by the shear blades. The carriage for the shearing mechanism comprises two side plates 252 which are bolted at their bottom ends to bosses on opposite sides of a vertically disposed cylinder 253. Near their upper ends, the side plates 252 are bolted to a cross bar 254, and bolted to the underside of the cross bar is a stationary shear blade 255, the cutting edge of which is designated at 256. Rotatably mounted on the outside of each of the side plates 252 at the leading and trailing edges thereof are two wheels 250 that run on laterally spaced pipe rails 261. The rails 261 are supported at their ends on posts 262, and are preferably inclined very slightly downhill toward the casting machine so that the carriage tends always to return by gravity to the end of the track adjacent the pinch roll unit 26.

A piston 263 is slidably disposed within the cylinder 253, and secured to the top end of the movable piston is a plate 264. Welded to the top of the plate 264 is a transversely extending bar 265, and bolted to the top surface thereof is a movable shear blade 266, the cutting edge of which is designated at 267. The bar 265 and shear blade 266 are engaged at their ends between pairs of spaced, parallel guides 270 which are welded to the side plates 252, said guides holding said movable shear blade to a vertical path of travel such that the edge 267 passes the stationary cutting edge 256 in a shearing relationship.

During the shearing operation, the bars are clamped firmly against the underside of the stationary blade 255 by means of a clamping plate 271 which is slidably supported on three laterally spaced guide rods 272 that are screwed into the plate 264; only one of said guide rods being visible in Figure 16. The plate 271 is pressed upwardly against heads 274 at the top ends of the rods 272 by springs 273, and in this upper-limit position, the top surface of the plate is flush with the top surface of the movable shearing blade 266. The three guide rods 272 are located so that the two bars pass between them; the center rod being between the bars, and the end rods being on the outer sides thereof. Recesses 275 are provided in the bottom surface of the stationary shear blade 255 to receive the heads 274 when the piston is at the top of its stroke.

Fluid under pressure is admitted to the bottom of the cylinder 253 through a flexible hose 276, which is connected to a hydraulic pump (not shown). The fluid is discharged into the cylinder when a limit switch (not shown) at the far end of the oven 30 is engaged and closed by the ends of the bars of metal that are being fed into the oven. Closing of this switch actuates a solenoid-operated by-pass valve on the hydraulic pump, causing the fluid discharged by the pump to be directed through the hose 276 into the cylinder, and as the fluid pressure builds up within the cylinder, the piston 263 moves upwardly, carrying the clamping plate 271 and shearing blade 266 with it.

As the bars are engaged and clamped against the shearing blade 255 by the plate 271, and as the edge 267 begins to bite into the metal, the carriage is carried along the rails 261 with the bars. Shearing is usually completed within a second or two, and the top surface of one of the sheared bars then engages and depresses a plunger 280 projecting downwardly through a

hole in cross bar 254 from a switch 281 mounted on top of the cross bar. Switch 281 is a normally-closed switch connected serially into the circuit of the solenoid on the by-pass valve, and is opened when plunger 269 is depressed, thereby restoring the by-pass valve to its original position and allowing the fluid in the bottom of the cylinder to escape. The switch 281 is protected from damage by a shield 279 having end plates 278 that are bolted to the side plates 252 of the carriage. As the piston 263 drops down to the bottom of the cylinder, the bars are released, and the carriage is freed to roll back to its original position.

The holding oven 30 forms no part of the present invention, and is merely included in the drawings by way of illustration. Accordingly no description of the oven is deemed necessary, other than to mention that the bars are fed into the oven through a flared throat 282 (Figure 1).

The mold cavity channels 65, 65' are wiped clean and lightly oiled on each circuit of the chain by means of oiling pads 285 and 286 (Figures 2 and 3) on the top of the machine. These pads are preferably of felt, and are attached to metal holders 290 which are swingably supported from transversely extending rods 291 that are attached to the top of the supporting structure 80. Torsion springs 292 hold the pads down against the surfaces of the mold blocks.

The operation of the casting machine is believed to be self-evident from the foregoing description. When the machine is first started up, the openings 213 in the box 35 through which molten metal flows into the spouts 36 are blocked off, and the furnace is tapped. Molten metal is allowed to fill the chambers 42 and 43, and to overflow through a notch 283 in the side of the box, running down a gutter 284 into pig molds, until the launders 34 and box 35 have been thoroughly heated and the temperature of the metal in the box is right for casting. The passages 213 are then uncovered, and metal is allowed to flow through the spouts 36 into the mold cavities. The mold cavities are usually plugged with a block so as to prevent the metal from flowing along the mold cavity until the latter has been filled. These blocks are carried through the machine on the front ends of the bars, and drop off when the bars push out of the machine at the exit end thereof. While the speed of the machine depends upon a number of variables, I have found that the most satisfactory operation for aluminum alloys is obtained with a chain speed of approximately 5 feet per minute.

When the machine is to be stopped, the tap hole 33 of the furnace is plugged, and when the chambers 42, 43 have emptied, the keys 206 are pulled out, releasing the spouts 36 so that they can travel through the machine with the now-solidified bars. The tips 197 are usually destroyed in the process, but these are inexpensive and are considered expendable.

While I have shown and described in considerable detail the presently preferred form of my invention, it will be understood that the description herein is merely illustrative, and that various changes may be made in the parts and components of the machine and in their arrangement relative to each other without departing from the broad scope of the invention as defined in the appended claims.

I claim:

1. A continuous casting machine comprising an endless chain of articulated mold blocks having

coolant passageways provided therein, means for revolving said endless chain in a non-circular path, a rotatable coolant distributor, flexible couplings connecting said distributor with the coolant passageways in said blocks, and means for rotating said distributor in synchronism with said endless chain of blocks.

2. A continuous casting machine comprising an endless chain of articulated mold blocks having coolant passageways provided therein, means for revolving said endless chain, means connecting the coolant passageways of each alternate block to the coolant passageways of an adjacent intervening block, a rotatable coolant distributor having coolant inlet and outlet chambers, flexible couplings connecting said distributor inlet chamber to the coolant passageways of said alternate blocks and connecting the distributor outlet chamber to the coolant passages of said intervening blocks, and means for rotating the coolant distributor in synchronism with the endless chain of blocks.

3. In a continuous casting machine, an endless revolvable chain of articulated mold blocks defining a travelling mold arranged to receive a stream of molten metal adjacent one end thereof, said blocks having coolant passageways formed therein, conduits connecting the coolant passageways of adjacent pairs of blocks, a source of coolant, and a conduit connecting the last of each of said pairs of blocks to come in contact with molten metal during each revolution of the chain with said coolant source, whereby coolant from said source flows first through the blocks of each of said pair that are the last to come in contact with molten metal during each revolution of the chain and therefrom flows through the blocks of each pair that are first to come in contact with molten metal during each revolution of the chain.

4. A machine for continuous casting of metal in bar form, said machine comprising a pair of endless chains of articulated mold blocks arranged adjacent one another and cooperating to form a straight mold cavity of uniform cross section, means for driving said chains of mold blocks so that the cooperating blocks thereof forming the mold cavity travel at the same rate of speed and in the same direction, each of said mold blocks having coolant passages provided therein, a source of fluid coolant under pressure, a pair of rotatable coolant distributor heads connected to said source, each of said heads being disposed to one side of and adjacent one of said chains of mold blocks, said heads being driven in the same direction as their respective chains and synchronized therewith, so that each head makes one revolution with each complete circuit of the chain, and conduit means connecting each of said distributor heads with the fluid passages in the mold blocks of its respective chain.

5. A machine for continuous casting of metal in bar form, said machine comprising a pair of endless chains of articulated mold blocks arranged adjacent one another and cooperating to form a straight mold cavity of uniform cross section, means for driving said chains of mold blocks so that the cooperating blocks thereof forming the mold cavity travel at the same rate of speed and in the same direction, each of said mold blocks having coolant passages provided therein, a source of fluid coolant under pressure, a pair of rotatable coolant distributor heads disposed to one side of and adjacent said chains of mold blocks, each of said heads being provided with 75 inlet and outlet chambers, said inlet chambers

being connected to said source of coolant and said outlet chambers being connected to a drain, means for driving said heads in the same direction and at the same speed as their respective chains, whereby each head makes one revolution with each complete circuit of the chain, and conduit means connecting said inlet and outlet chambers of said distributor heads with said fluid passages in said blocks, whereby fluid coolant is circulated through said passages to cool the blocks.

6. In a continuous casting machine of the character described, having an endless chain of articulated metal mold blocks, each block having a channel formed in its outer face, said blocks cooperating so that the channels therein form a continuous mold cavity of uniform cross section, each of said blocks having a plurality of parallel coolant passageways formed therein closely adjacent the bottom surface of said channel, there being a pair of header passageways connecting said coolant passageways together at each end thereof, means for delivering coolant to one of said header passageways and for withdrawing it from the other, and a massive stiffening rib extending from the face of the block opposite that in which the mold channel is formed, said rib being maintained at a relatively constant temperature by the coolant in said passageways, the mass of said rib being substantially greater than the mass of metal lying between said coolant passageways and the bottom of said mold channel, said rib serving to resist the tendency of said mold block to bow outwardly as the metal between said coolant passageways and the bottom of said channel is heated and expanded by the metal poured into the mold cavity.

7. A continuous casting machine comprising a pair of endless chains of articulated mold blocks arranged adjacent one another and cooperating to form a straight mold cavity of uniform cross section, each of said blocks having coolant passageways formed therein closely adjacent the surface of said mold cavity, a coolant distributor comprising a rotatable hollow head associated with each of said endless chains, each of said heads being divided internally by a partition into separate inlet and outlet chambers, coolant circulating means connected to said heads so as to deliver coolant to said inlet chambers and to remove coolant from said outlet chambers, a plurality of flexible coolant pipes connecting the inlet chamber of each of said heads to the inlet sides of the coolant passageways in the mold blocks of the associated chain, a plurality of flexible coolant pipes connecting the outlet chamber of each of said heads to the outlet sides of the coolant passageways in the mold blocks of the associated chain, and motor means for driving said endless chains in opposite directions, and for driving each of said distributor heads in the same direction and at the same rotational speed as its associated chain.

8. A continuous casting machine comprising a pair of endless chains of articulated mold blocks arranged adjacent one another and cooperating to form a straight mold cavity of uniform cross

section, each of said blocks having coolant passageways formed therein closely adjacent the surface of said mold cavity, a coolant distributor comprising a rotatable hollow head associated with each of said endless chains, each of said heads being provided with inlet and outlet hose fittings, coolant circulating means connected to said heads so as to deliver coolant to said inlet fittings and to remove coolant from said outlet fittings, a plurality of flexible hoses connecting the inlet fittings of each of said heads to the inlet sides of the coolant passageways in the mold blocks of the associated chain, a plurality of flexible hoses connecting the outlet fittings of each of said heads to the outlet sides of the coolant passageways in the mold blocks of the associated chain, and motor means for driving said endless chains in opposite directions, and for driving each of said distributor heads in the same direction and at the same rotational speed as its associated chain.

9. A continuous casting machine comprising a pair of endless chains of articulated mold blocks arranged adjacent one another and cooperating to form a straight mold cavity of uniform cross section, each of said blocks having coolant passageways formed therein closely adjacent the surface of said mold cavity, a coolant distributor comprising a rotatable head associated with each of said endless chains and having a plurality of inlets and outlets, a set of flexible hoses connecting said inlets to the inlet sides of the coolant passageways in the mold blocks of the associated chain, a second set of flexible hoses connecting said outlets to the outlet sides of the coolant passageways in the mold blocks of the associated chain, coolant circulating means connected to said inlets and outlets so as to circulate coolant through said hoses and the passageways in said mold blocks, and motor means for driving said endless chains in opposite directions, and for driving each of said distributor heads in the same direction and at the same rotational speed as its associated chain.

JOSEPH L. HUNTER.
